Primary Examiner — Rashida Johnson(74) *Attorney, Agent, or Firm* — Fleit Gibbons Gutman Bongini & Bianco PL; Jon A. Gibbons(57) **CLAIM**

The ornamental design for a percussion instrument, as shown and described.

DESCRIPTION

FIG. 1 is a front isometric view of a percussion instrument, showing our new design;

FIG. 2 is a front view thereof;

FIG. 3 is a top view thereof;

FIG. 4 is a bottom view thereof;

FIG. 5 is a right side view thereof; and,

FIG. 6 is a left side view thereof.

The broken lines represent the portions of the percussion instrument, which form no part of the claimed design.
